UNITED STATES PATENT OFFICE.

JOHN H. IRWIN, OF CARLINVILLE, ILLINOIS.

CATTLE-PUMP.

Specification of Letters Patent No. 22,653, dated January 18, 1859.

To all whom it may concern:

Be it known that I, JOHN H. IRWIN, of Carlinville, in the county of Macoupin and State of Illinois, have invented a new and 5 Improved Automatic or Self-Acting Pump Designed for Raising Water for Stock; and I do hereby declare that the following is a full, clear, and exact description of the same, reference being had to the annexed drawings, making a part of this specification, in 10 which—

Figure 1, is a side sectional view of my improvement taken in the line α , α , Fig. 2. Fig. 2, is a plan or top view of ditto. 15 Similar letters of reference indicate corresponding parts in the two figures.

This invention relates to an improvement in water pumping devices in which stock are made to raise the water they drink by 20 means of their own weight or gravity.

The invention consists in attaching jointed or rising and falling platforms by means of ropes or chains to a drum which has a pulley of comparatively large diameter 25 placed loosely on it, and connected with the drum, when the latter is turned in one direction only, the drum having a weight attached to it, the pulley being connected with a pump, and the whole arranged to operate 30 as hereinafter shown and described so as to effect the desired object.

To enable those skilled in the art to fully understand and construct my invention I will proceed to describe it.

35 A, represents a suitable framing in which two platforms B, B', are placed, the outer ends of said platforms being connected by joints or hinges α , α , to the frame so that the inner ends may rise and fall. The two 40 platforms are of equal width and nearly equal in width to the space between the sides of the framing, sufficient room being allowed to insure a free movement of the platforms.

45 To the inner ends of both platforms B, B', ropes or chains b , are attached. The upper ends of these chains are attached to a drum C, which has two different diameters c , d , the chains being attached to the smaller 50 portion c , of the drum. To the larger portion d , of the drum C, a ratchet D, is attached. This ratchet is secured to the end of the larger part d , of the drum C, and it adjoins a pulley D', of comparatively large diameter, which pulley is 55 placed loosely on the drum, or on its axis

or shaft. This pulley has a pawl e , attached to it, said pawl catching into the teeth of the ratchet D, and causing the pulley to be rotated with the drum when the latter is turned in one direction as indicated by arrow 1. To the larger portion d , of the drum C, a rope or chain E, is attached. This chain has a weight F, at its lower end. 65

The framing A, may be sunk about two feet into the ground and the platforms B, B', be about one foot above the surface so that the platforms will have a rise and fall of three feet. The pulley D, may be six 70 feet in diameter. I do not confine myself to any particular dimensions but perhaps the above will be generally used.

When the weight F, is down to its fullest extent the platforms B, B', are elevated 75 to their extreme height, the weight F, being very considerably heavier than is necessary for this purpose alone.

The pulley D', is connected by a belt with the wheel or shaft of a chain pump, or it 80 may be connected with any form of pump by any suitable means.

The device above described is placed at the entrance of an inclosure G, within which are the pump and well. The cattle 85 in order to get into this inclosure must necessarily pass over the platforms B, B', and in so doing the platforms are depressed and the weights F, raised, in consequence 90 of the chains b , rotating the drum C, the pulley D', remaining stationary. The chain E, of the weight F, is of course wound on the larger portion d , of the drum in a reverse direction to the chains b . As an animal passes off the platform into the inclosure the weight F, rotates the drum C, in the direction of arrow 1, and the pulley D', will consequently be rotated with it, by means of the pawl e , and ratchet D, and the pump actuated, the weight at the same time raising the platforms B, B', to their original position so that a succeeding animal in entering the inclosure will in its turn actuate the pump in like manner. It 100 will be seen that the animals actuate the pump in passing both in and out of the inclosure and a trough therefore may always be kept full of water for their use.

By this invention a durable self pumping device is obtained. It is perfectly immaterial as regards the weight of the animals, they cannot injure the device as the 110

pump is operated by a constant power, viz, the weight F, the animals merely raising the weight and not acting by their gravity directly on the pump. The device therefore 5 is not liable to get out of repair which might otherwise be the case in consequence of the varying weight of cattle or in their passing over the platforms at an immoderate speed.

I am aware that rising and falling platforms have been employed and connected with pumps in such a way that animals in passing over them would actuate the pump, but I am not aware of any arrangement like 10 the one herein described whereby the animals do not directly actuate the pumps but 15 only raise a weight which serves as a con-

stant power to actuate the pump. I do not claim therefore the use of rising and falling platforms separately considered; but,

I do claim as new and desire to secure by 20 Letters Patent,

The platforms B, B', weight F, drum C, and pulley D', placed loosely on drum C, and connected with it by the pawl e, and ratchet D, the whole being combined and 25 arranged to operate as and for the purpose set forth.

JOHN H. IRWIN.
